THERMOREGULATOR

Filed Dec. 15, 1939

UNITED STATES PATENT OFFICE

2,264,335

THERMOREGULATOR

John Leonard Schwartz, Philadelphia, Pa., assignee to Philadelphia Thermometer Company, Philadelphia, Pa., a partnership

Application December 15, 1939, Serial No. 309,329

19 Claims. (Cl. 200—141)

This invention relates to thermo-regulators, and particularly to condition-responsive regulators, comprising a continuation in part of application No. 174,320, filed November 13, 1937.

There are many situations in which it is desirable to effect the operation of a given electrical circuit as a function of the variation of a given condition, as for instance conditions of temperature, pressure, density, liquid level, etc. The invention herein relates to devices responsive to any of such conditions, but for purely illustrative purposes, however, it will be described as it is provided for thermal conditions.

In the art of thermally regulated circuits, a large part of the field is occupied by thermometers incorporated contacts in the form of wires extending into the capillary tube in which a column of mercury is caused to move by the changes in temperature incident upon the mercury, and which column makes or breaks the contact between the wires. Although it is possible to obtain with those devices control elements which are sensitive to very minute changes in temperatures, measured in fractions of degrees, yet the sensitivity has certain well defined limits, and the accuracy of the elements is not only merely passably satisfactory, but also varies during the life of the instrument.

The factors involved might be briefly recited for a better understanding of the problem. For responses to small thermal changes it is necessary to have a large volume of mercury in the bulb, or other housing, communicating with an extremely small capillary or bore in the glass column. Obviously the greater the volume of mercury in the bulb and the smaller the bore in the glass, the greater the distance the meniscus of the mercury will travel for a given small change in the temperature to which the bulb is exposed. This has been materially affected by the previous practice of embedding a fine contact wire, such as of platinum or the like, in the glass column in position to be engaged by the moving mercury column, as this has many disadvantageous and undesirable attributes. It is necessary to break the glass column, insert the fine wire, and then fuse the severed glass portions and the wire together while trying to maintain the alignment of the bore in each such portion, and this frequently results in a misalignment such as effects a constriction in the bore to vary the flow of mercury through it. The wire must be very fine in order to avoid blocking the bore or passage completely, and it thus cannot carry any appreciable load, and is, of course, possessed

of high resistance. Such wire inevitably effects a partial block of the channel or bore, so as to vary the flow of mercury past it from that occurring in the remainder of the bore. The fine wires used necessitate the use of relays to secure a given power operation. Most undesirable of all, perhaps, is the factor of the contact being made between the moving mercury column and the fixed metal contact. This latter finds the closing of the circuit through the contact affected by the oxidation or other material floating on the surface of the mercury, either as an incident of past arcing between the mercury and platinum or other wire contact, or because of impurities in the mercury. This changes the resistance factors involved and changes the timing of the circuit making or breaking, and by the erosion or corroding of the wire contacts, due to pitting and the like due to arcing between the mercury and wire, still further changes the timing and resistance involved until through erosion the wire contact disappears and the circuit controlling ceases. The breaking of the circuit of such a device is variable in timing, owing to the fact that the normal surface tension of the mercury tending to pull it away from the contact to form a meniscus on its upper end, is partially nullified by its adhesion to the contact, pursuant to "wetting" same, so that there is no sharp sudden break, but only a delayed protracted break which accentuates the arcing and also affects the timing of the break, as will be clear.

It is among the objects of this invention: to provide a thermo-regulator which obviates disadvantages attaching to the prior art; to provide a thermo-regulator in which the make and break is through two columns of mercury; to provide a thermo-regulator responsive to extremely minute changes in condition for sensitive action; to provide a thermo-regulator of extreme accuracy in make and break pursuant to a predetermined change in condition; to provide a thermally actuated regulator of simplicity and high efficiency; to provide a thermo-regulator wherein the terminals for the controlled circuit enter the respective capillary bores in such a manner as to form a perfect contact without obstructing or otherwise affecting the travel of the mercury; to provide a thermo-regulator wherein the closing of the circuit by the meeting of the two columns of mercury takes place between the juxtaposed edges of the two columns instead of by the complete merging of the menisci of the two columns, as a corollary of which the breaking of the circuit by contraction of the columns gives an in-

stantaneous circuit break thereby promoting accuracy of operation and greatly increased sensitivity over prior constructions; to provide a novel partition for separating the two columns in the approximate area of contact making; to provide an overflow pocket so arranged and associated with the contact making point of the two mercury columns as to increase the efficiency of operation of the regulator; to provide a novel insulation for the terminal wires of the instrument whereby deleterious action between the mercury and such wires is eliminated; to provide means for bringing the circuit wires to the exterior of the regulator without danger of short circuits developing; and to provide other improvements as will hereinafter appear.

In the accompanying drawing Fig. 1 represents a sectional elevation of a thermo-regulator embodying one form of the present invention; Fig. 2 represents an enlarged sectional detail of the control end of the regulator; Fig. 3 represents a section on line 3—3 of Fig. 2; Fig. 4 represents a section on line 4—4 of Fig. 1; Fig. 5 represents a sectional detail on an enlarged scale of the overflow pocket; Fig. 6 represents an elevation of a portion of the control end viewed at ninety degrees from the elevation of Fig. 1; and Fig. 7 represents a section on line 7—7 of Fig. 1.

Referring to the drawing one form of thermo-regulator is shown consisting of an elongated glass member 10 which is preferably made up of a bulb 11, a contact control head 12, and an intermediate neck 13 interconnecting the parts 11 and 12 and of suitable length to meet conditions of use. The bulb 11 is formed with a longitudinally disposed partition 14 which thus divides it into two relatively long chambers 15 and 16 lying side by side and paralleling the axis of the member 10. The neck 13 is an integral extension of the bulb 11 being a glass rod solid except for two capillary through bores 17 and 18 which generally parallel the axis of the neck 13. The bore 17 communicates at one end with the chamber 15 and the bore 18 communicates at one end with the chamber 16. Thus when the respective chambers 15 and 16 are filled with mercury or other temperature responsive medium the two bores 17 and 18 provide channels for columns of mercury rising from the respective bulb chambers and functioning as two thermometers disposed side by side.

The control head 12 forms a receptacle 20 containing a glass post 21 which rises substantially axially from the sealed bottom of the receptacle 20 where it joins the top of the neck 13. This post 21 is provided with two longitudinally disposed capillary channels 22 and 23, the lower ends of which respectively communicate with the bores 17 and 18, and the upper ends thereof terminate at a common level. At this level the body of glass between the channels 22 and 23 is so reduced in thickness as to become a relatively thin partition 25, the upper edge of which is formed with a depressed notch 26 through which the side edge of one mercury column meets the side edge of the other to close the control circuit. In this connection it should be noted that it is extremely important that the bottom of the notch 26 terminates substantially in the horizontal plane which passes through the termination level common to the bores 22 and 23. The common level forms an inlet to an overshoot or expansion chamber, 27 having a laterally turned nozzle

30 terminating in close proximity to the wall of the receptacle 20.

In order to indicate that contact has been made between the two columns of mercury a conductor wire 31 has one end sealed in the post 21 to terminate in the channel 22 while its opposite end is sealed through the wall of the receptacle 20. In a like manner a conductor 32 leads from the channel 23 to the outside of the receptacle 20 at a point preferably axially spaced from the point from which the conductor 31 protrudes. Preferably both conductors 32 and 31 emerge respectively in lateral grooves 33 and 34 formed by a corrugated contour of the extended end of the receptacle 20. The groove 33 seats a conducting strip 35 which is electrically bonded to the conductor 32 and also to a terminal wire 36 leading through the end of a protective housing 37 for connection to a suitable socket or binding post as the case may be. The groove 34 in like manner seats a strip 38 which is electrically bonded to the conductor 31 and also to a terminal wire 40 leading through the end of the housing 37 in close proximity to the terminal wire 36 so that both wires are convenient for contact with an electrical circuit. The wire 40 forms a connection with a suitable socket or binding post as the case may be for operative association with conductors leading to a suitable indicator. It should be noted that where the two wires 31 and 32 enter the respective channels 22 and 23 the latter are somewhat enlarged in diameter so that contact is always ensured between a wire and the mercury while the wire does not obstruct the travel of the mercury along the channel. Another advantage of this is that as the mercury rises and falls the enlarged channel portions prevent any separation of the mercury in each column caused by entrapped air or gas.

As a means to prevent direct contact between the conductors 31 and 32 and any mercury in the receptacle 20 to thus cause deleterious action, each conductor is encased in a glass sleeve 41 or 42 which is slipped into place and fused to the conductor. Preferably each sleeve terminates just short of the point where it enters the glass to thereby allow sufficient flexibility for proper bending of the conductors to assembled position. While the glass sleeve-like insulation has been found to give excellent results the invention is not limited to this specific insulation as other forms of insulation may be found entirely practical. Obviously the advantageous use of the insulated wires 31 and 32 in the mercury reservoir or chamber may be availed of with the electrode ends terminating in a single column of mercury if this is desired.

For the purpose of anchoring the housing 37 over the end of the control head 12, a length of electric tape 43 or other suitable insulating material is wound about the end portion of the head 12 to cover the terminal wires 36 and 40 and strips 35 and 38. The housing 37 is anchored to the bulb 11 by filling one of the circumferential grooves of the corrugated bulb end with a cementitious material 44, such, for example, as litharge as this has been found to give excellent results for uniting the metal housing to the glass.

In the operation of the thermo-regulator it will be assumed that it is to function as a control, or an alarm, or an indicator when the temperature of the test medium reaches, for example, two hundred degrees. The instrument is

particularly adapted to the creation of an initial setting for temperature responsiveness and for change therein. It being recognized that the chamber 20 will be provided with an initial quantity of mercury as a surplus or reserve supply in the reservoir, the settings are made or changed in a manner analogous to earlier devices incorporating such overflow or overshoot expansion chamber 27. This initial setting or any changes that may be desired to be made in the setting either above or below the initial setting are accomplished either by first ascertaining the exact difference between the temperature at which the two adjacent columns of mercury have first established lateral contact between them with no excess mercury in the expansion chamber 27, and the temperature at which the entire expansion chamber is completely filled as a continuation of the mercury columns in the capillary bores. With this information it will obviously be a simple matter to change the temperatures effective upon the bulbs 15 and 16 either to force out undesired mercury, if the initial setting is to be raised above the illustrative 200° setting, or to pick up additional mercury from the surplus in the chamber or reservoir 20, as by tilting the instrument and causing the restricted orifice or neck 30 to dip into the mercury as the temperature from the bulbs 15 and 16 is lowered as this draws additional mercury into the expansion chamber 27 to increase the amount in the capillaries. If the initial differential for the chamber 27 be unknown to the operator he may change the setting by manipulating the instrument at any time that the expansion chamber 27 is appreciably less than half filled as the entrapped mercury can be shaken from one end of the chamber to the other and then pushed out of the expansion chamber by the globule of entrapped mercury-separating gas or air as the temperature on the bulbs 15 and 16 rises.

The use of the expansion chamber 27 as noted, is analogous to the earlier forms of this particular construction in which two electrodes extend into the same single mercury column.

However the settings are varied it will be appreciated that whatever the selected temperature the regulator is susceptible to insertion into the top of a container with the bulbs 15 and 16, and frequently with the double capillary column 13 as well, immersed in the fluid or liquid, the temperature of which is to actuate the regulator. The regulator being thus suitably installed is now ready for use and every time a temperature of the illustrative two hundred degrees or other predetermined setting is reached the circuit including the conductors 31 and 32 is closed by the bridging of the mercury from bores 17 and 18 at the notch 26. In this connection it should be noted that the relatively thin partition with its re-entrant notch ensures an exact meeting of the bores at that point and avoids the objection present in angularly divergently bored regulators of the mercury from one bore working over into the other bore to thus introduce erroneous results.

It will be understood that in completing the regulator the upper end of the bulb portion 12 is left open temporarily until after the mercury is properly disposed in the regulator in order that some inert gas such as nitrogen or hydrogen can be introduced under suitable pressures as to minimize both the effect and the degree of arcing. The open end is then fused and sealed as at 45 to entrap the gas under its pressure.

It is to be understood that the double bored integral tube 13 may be of any length from an inch or so to two or three feet, of straight or angle form, without appreciable change of the upper 5 and lower portions and to meet varying depth conditions so as to secure the suitable exposure of the bulbs 15 and 16 to the incident heat conditions.

It is an important object and feature of this 10 invention that the device be adapted particularly for immersion and for successful immersed use, to which end all of the wires and electrodes are so housed or insulated that contact can only be made at the extreme end of the instrument. It is noteworthy that this important effect is produced without providing a supplemental shielding envelope about the assembly and especially about the double capillary bore 13, which latter being exposed in non-insulated relation may also contribute to the thermo-responsiveness of the 15 whole.

It is a further important and novel feature 20 of the invention that the extremely thin partition 25, especially with a notch 26 as shown, secures a sensitive constant circuit-closing function and also secures the identical instantaneous certain circuit opening by the knife edge separating function of the partition. The capillary bores 22 and 23 are almost parallel in their extent and 25 the contained columns move almost in parallel lines in moving toward and from the thermal circuit regulation point with a minimum of lateral motion.

Another advantageous element of the instant 30 invention lies in the fact that the greatest diameter of the entire assembly lies in the supporting head so that the instrument can be inserted into very small apertures and be supported from the tip end in such small apertures, which is a further feature facilitating the use of the invention in immersion situations.

Having thus described my invention, I claim:

1. In thermo-regulators, a section of drawn 35 glass tubing having two parallel bores, the bores at one end merging into a single channel, bulbs 40 attached to the tubing in communication with the respective bores, mercury in the respective bulbs and bores and forming individual thermometers in a common tubing, electrodes in intimate electrical engagement with the mercury in each thermometer.

2. In thermo-regulators, a section of drawn 45 glass tubing having two parallel independent relatively closely spaced bores extending longitudinally within the boundary surfaces of a common section, each of said bores being enlarged at one end of the section to form a bulb of a thermometer, mercury disposed in each relatively communicating bulb and bore, a bored stem 50 communicating with and common to both bores at the other end of said section to lead them into a single common channel, electrodes in electrical engagement with the mercury of each thermometer.

3. In thermo-regulators, a section of drawn 55 glass tubing having a pair of parallel spaced mercury bores extending longitudinally of the section, the section at one end being enlarged to form bulbs communicating with the respective 60 bores, and at the other end being provided with a common channel having an open mouth and being in communication with both bores, electrodes having portions in the passage formed of 65 bulb and bore on each side of the section, a glass 70

housing surrounding the common channel and electrodes, and connectors in the housing.

4. In thermo-regulators, a section of drawn glass tubing having two parallel bores, the bores at one end merging into a single channel having an outlet, bulbs attached to the tubing in communication with the respective bores, mercury in the respective bulbs and bores and forming individual thermometers in a common tubing, electrodes in intimate electrical engagement with the mercury in each thermometer, said single channel comprising an enlarged reservoir into which both bores open substantially at their junction point spaced from said outlet.

5. In thermo-regulators, a section of drawn glass tubing having two parallel bores, said tubing reduced at one end whereby the space between the bores is occupied by a thin partition the outer edge of which forms a narrow path across which the menisci of mercury in the bores can spread laterally to establish contact, bulbs attached to the tubing in communication with the respective bores, mercury in the respective bulbs and bores forming individual thermometers in a common tubing, electrodes in electrical engagement with the mercury in each thermometer.

6. In thermo-regulators, two mercury thermometers joined into an integral unit at their upper ends, the said upper ends comprising an integral unit of an enlarged overflow receptacle joining a joint column containing two thermometer bores, said bores separated at the line of jointure of the receptacle by a thin partition forming a narrow transverse path for lateral mutual joining motion of the respective mercury columns of the respective thermometers, and so arranged that the closing of a physical path of mercury across said partition by the rising of the mercury in the said respective bores, is substantially instantly followed by overflow of excess mercury into said receptacle.

7. In thermo-regulators, a section of drawn glass tubing having two parallel bores, said tubing reduced at one end whereby the space between the bores is occupied by a thin partition the outer edge of which has a notch which forms a narrow path across which the menisci of mercury in the bores can spread laterally to establish contact, bulbs attached to the tubing in communication with the respective bores, mercury in the respective bulbs and bores forming individual thermometers in a common tubing, electrodes in electrical engagement with the mercury in each thermometer.

8. A thermo-regulator comprising an elongated member formed by two reservoirs, an upper tubular part, and an intermediate length of drawn glass having two capillary bores communicating respectively with said reservoirs and with said tubular part, mercury in said reservoirs to travel through said bores under applied heat, conducting wires respectively entering said bores for contact with the mercury therein, said wires leading through said tubular part to the exterior thereof, and means at the exit end of said bores for causing juxtaposed side edges of said mercury columns to contact to close a circuit.

9. A thermo-regulator comprising an elongated member formed by two reservoirs, an upper tubular part, and an intermediate length of drawn glass having two capillary bores communicating respectively with said reservoirs and with said tubular part, mercury in said reservoirs

to travel through said bores under applied heat, conducting wires respectively entering said bores for contact with the mercury therein, said wires leading through said tubular part to the exterior thereof, and means at the exit end of said bores for causing juxtaposed side edges of said mercury columns to contact to close a circuit prior to the uniting of said mercury columns into a common meniscus.

10. A thermo-regulator comprising an elongated member formed by two reservoirs, an upper tubular part, and an intermediate length of drawn glass having two capillary bores communicating respectively with said reservoirs and with said tubular part, mercury in said reservoirs to travel through said bores under applied heat, conducting wires respectively entering said bores for contact with the mercury therein, said wires leading through said tubular part to the exterior thereof, means at the exit end of said bores for causing juxtaposed side edges of said mercury columns to contact to close a circuit, and means to substantially insulate that portion of said wires in said tubular part from contact with said mercury.

11. A thermo-regulator comprising an elongated member formed by two reservoirs, an upper tubular part, and an intermediate length of drawn glass having two capillary bores communicating respectively with said reservoirs and with said tubular part, mercury in said reservoirs to travel through said bores under applied heat, conducting wires respectively entering said bores for contact with the mercury therein, said wires leading through said tubular part to the exterior thereof, said bores being separated by a relatively narrow partition merging into a thin bladelike edge in the plane of the exits of said bores, and means at the exit end of said bores for causing juxtaposed side edges of said mercury columns to contact to close a circuit.

12. A thermo-regulator comprising an elongated member formed by two reservoirs, an upper tubular part, and an intermediate length of drawn glass having two capillary bores communicating respectively with said reservoirs and with said tubular part, mercury in said reservoirs to travel through said bores under applied heat, conducting wires respectively entering said bores for contact with the mercury therein, said wires leading through said tubular part to the exterior thereof, said bores being separated by a relatively narrow partition merging into a thin bladelike edge in the plane of the exits of said bores, and a port through said edge to cause juxtaposed side edges of said mercury columns to contact to close a circuit.

13. In thermo-regulators, a drawn glass column containing two parallel capillary bores, bulbs containing mercury and communicating with each bore to form mercury columns, a terminus integral with one end of the column containing two bores separated by a narrow partition having an outer edge forming a narrow path across which mercury in the bores has slight lateral travel to establish contact between the mercury columns, wire electrodes mounted in the terminus in engagement with the respective columns, an overflow chamber mounted on the terminus of enlarged diameter relative to the bores and in such position as to receive mercury rising over the outer edge of the partition, a housing integral with the terminus and the column arranged to house the said electrodes and to receive and support excess mercury initially in

the chamber, said electrodes having free ends extending through the housing toward its free end.

14. In thermo-regulators, a column containing two parallel capillary bores, bulbs containing mercury and communicating with each bore to form mercury columns, a terminus integral with one end thereof containing two bores separated by a narrow partition having an outer edge forming a narrow path across which mercury in the bores has slight lateral travel to establish contact between the mercury columns, wire electrodes mounted in the terminus in engagement with the respective columns, an overflow chamber mounted on the terminus to enlarged diameter relative to the bores and in such position as to receive mercury rising over the outer edge of the partition, a housing integral with the terminus and the column arranged to house the said electrodes and to receive and support excess mercury initially in the chamber, said electrodes having free ends extending through the housing toward its free end, and a cap mounted on the free end of the housing for supporting the regulator and having end terminals, and connectors electrically joining the respective electrodes and said terminals.

15. In thermo-regulators, a column containing two parallel capillary bores, bulbs containing mercury and communicating with each bore to form mercury columns, a terminus integral with one end thereof containing two bores separated by a narrow partition having an outer edge forming a narrow path across which mercury in the bores has slight lateral travel to establish contact between the mercury columns, wire electrodes mounted in the terminus in engagement with the respective columns, an overflow chamber mounted on the terminus of enlarged diameter relative to the bores and in such position as to receive mercury rising over the outer edge of the partition, a housing integral with the terminus and the column arranged to house the said electrodes and to receive and support excess mercury initially in the chamber, said electrodes having free ends extending through the housing toward its free end, the free end of said hous-

ing having a series of peripheral grooves, metal bands in respective grooves in electrical engagement with said electrodes, a cap on said free end with terminals electrically connected with said bands.

16. In thermo-regulators, a section of drawn glass tubing, a mercury bulb communicating therewith, said tubing having an overflow end, a closed reservoir surrounding the overflow end of the tubing, a pair of electrode wires embedded in the tubing and extending longitudinally within the reservoir through a wall thereof to termination in electrical engagement with elements external of the reservoir.

15 17. In thermo-regulators, a section of drawn glass tubing, a mercury bulb communicating therewith, said tubing having an overflow end, a closed reservoir surrounding the overflow end of the tubing, a pair of electrode wires embedded in the tubing and extending longitudinally within the reservoir through a wall thereof to termination in electrical engagement with elements external of the reservoir, and insulation on said wires.

20 18. In thermo-regulators, a section of drawn glass tubing, a mercury bulb communicating therewith, said tubing having an overflow end, a closed reservoir surrounding the overflow end of the tubing, a pair of electrode wires embedded in the tubing and extending longitudinally within the reservoir through a wall thereof to termination in electrical engagement with elements external of the reservoir, and insulation on said wires, comprising fused glass.

25 19. In thermo regulators, a glass envelope having a thin median partition dividing the envelope into parallel contiguous mercury bulbs, glass means defining two mercury bores, said glass means merging into the glass envelope with the respective bores in communication with the respective bulbs, and mercury in both bulbs, the bulbs being disposed in such close adjacency that expansion of the mercury in the bulbs incident to heating the envelope is equal in both bulbs and forces the same volume of mercury into both of said bores.

JOHN LEONARD SCHWARTZ.
